United States Patent Office

Des. 184,184
Patented Dec. 30, 1958

184,184

RADIAL SAW

Joseph R. Mango, Midlothian, Ill., and Russell E. Hughes,
St. Louis, Mo., assignors to The Emerson Electric Manufacturing Company, St. Louis, Mo., a corporation of Missouri

Application August 29, 1957, Serial No. 47,539

Term of patent 14 years

(Cl. D93—3)

Fig.1

Fig.2

Figure 1 is a top plan view of a radial saw embodying our new design;

Figure 2 is a side elevational view thereof;

Figure 3 is a side elevational view thereof; looking at the side opposite to that in Figure 2;

Figure 4 is a front end elevational view thereof; and

Figure 5 is a rear end elevational view thereof.

The essential features of our design reside in the portions shown in full lines.

We claim:

The ornamental design for a radial saw, substantially as shown and described.
